UNITED STATES PATENT OFFICE.

HARRY E. SCHOENHUT, OF PHILADELPHIA, PENNSYLVANIA, ASSIGNOR TO GEORGE E. STUDDY, OF LONDON, ENGLAND.

DESIGN FOR A TOY ANIMAL FIGURE.

Application filed February 8, 1928. Serial No. 25,271. Term of patent 14 years.

To all whom it may concern:

Be it known that I, HARRY E. SCHOENHUT, a citizen of the United States, residing at E. Hagert and Sepviva Streets, in the city of Philadelphia, county of Philadelphia, and State of Pennsylvania, have invented a new, original, and ornamental Design for a Toy Animal Figure, of which the following is a specification, reference being had to the accompanying drawing, forming a part thereof, and showing in

Fig. 1 a front view and in Fig. 2 a side view of the toy animal figure embodying my new design.

I claim:

The ornamental design for a toy animal figure substantially as shown.

HARRY E. SCHOENHUT.
